UNITED STATES PATENT OFFICE.

WESLEY M. SCOTT, OF COLUMBUS, OHIO.

ROTATABLY-MOUNTED WHEEL.

SPECIFICATION forming part of Letters Patent No. 737,289, dated August 25, 1903.

Application filed November 25, 1901. Serial No. 83,524. (No model.)

To all whom it may concern:

Be it known that I, WESLEY M. SCOTT, a citizen of the United States, residing at Columbus, in the county of Franklin and State of Ohio, have invented a certain new and useful Improvement in Rotatably-Mounted Wheels, of which the following is a specification.

My invention relates to the improvement of wheels, and has particular relation to that class of wheels which are rotatably mounted on shafts or spindles.

The objects of my invention are to provide an improved construction of wheel wherein superior means are provided for retaining oil and distributing the same to the axle or spindle upon which the wheel is mounted, to provide an improved construction of wheel-hub having receptacles or pockets for the reception of accumulated dirt or dust, and to produce other improvements, the details of construction of which will be more fully pointed out hereinafter. These objects I accomplish in the manner illustrated in the accompanying drawings, in which—

Figure 1 is an outer face view of my improved wheel. Fig. 2 is a sectional view on line $\alpha\alpha$ thereof, and Fig. 3 is an inner side view.

Similar numerals refer to similar parts throughout the several views.

1 represents the rim of a wheel, which in the drawings is shown in the form of a car-wheel, although it will be obvious that my invention may be applied to wheels for other purposes.

2 represents suitable spokes, which radiate from a central hub or boxing 3. As indicated in the drawings, the body of the hub or boxing is provided with a central spindle-opening 4, which is designed to receive the spindle 5 of an axle or shaft 5^a. The inner end of the hub 3 is extended beyond the body of the wheel and about the mouth of the opening 4 may be recessed to receive an axle-shoulder 6. The forward side of the hub 3 is formed with a rim-like extension 7, the continuity of which is broken by an opening 8 therein, which is shown in Fig. 1. About the central bearing-opening 4 of the hub and in

the body of said hub is formed an annular oil-chamber 9, the latter being intersected at intervals with strengthening-lugs 10. This

chamber 9 is through the medium of suitably-formed separated openings 11 made to communicate at different points with the shaft or spindle bearing-opening 4. The forward side of the hub-body has formed therein an oil-feed opening which is closed by a suitable plug 12, this feed-opening being formed, as indicated more clearly in Fig. 1 of the drawings, between the separated ends of the forward extension 7 of the hub. In the formation of the hub-body 3 I provide at intervals rounded projections 13, the interiors of which communicate with the body of the oil-chamber and form oil-chamber recesses or pockets. Leading into each of these pockets through the inner side or end of the hub-body is an internally-threaded opening, which is normally closed by the plug 14.

In utilizing my invention the desired quantity of oil is introduced through the oil-feed opening by the temporary removal of the plug 12, the oil thus supplied to the chamber 9 passing through the openings 11 to the surface of the spindle 4 and insuring the latter being oiled. In the revolution of the wheel it is obvious that any dirt or foreign particles which might accumulate within the oil-chamber will through centrifugal motion of the hub be thrown outward and that the pockets or recesses 13 will serve to receive and form a lodging-place for the dirt thus expelled. The dirt thus accumulated in said pockets may be removed through the cleaner-openings, which are normally closed by the plugs 14.

By providing the opening or break 8 in the rim extension 7 it will be seen that the insertion of a cotter-pin 15 through the usual pin-opening in the outer end of the spindle is permitted. It will be understood that the outwardly-projecting hub-rim 7 will serve as a hood for the end of the spindle and guard the latter against injury or breakage.

It will here be noted that the closure-plug 12 is located within the opening 8 in the flange 7, with its outer end projected across the adjacent end of the pin or key 15, thereby preventing accidental displacement of the pin or key when the plug is in position, and hence this plug serves a double function.

From the construction herein shown and described it will be seen that not only is pro-

vided simple and effective means for retaining and distributing the oil, but that improved means are provided in conjunction therewith for the collection and removal of 5 dirt and foreign matter.

Having now fully described my invention, what I claim, and desire to secure by Letters Patent, is—

1. The combination with an axle-spindle 10 having a diametric opening formed through the outer portion thereof, of a wheel rotatably mounted upon the spindle in rear of the opening therethrough and provided with an annular oil-chamber in communication with 15 the spindle-receiving opening of the hub, the outer end of the hub being provided with an outwardly-directed substantially cylindrical flange projected in front of the adjacent end wall of the hub and having a portion omitted, 20 a pin or key fitted to the opening in the spindle to prevent displacement of the hub, the outer end wall of the hub being provided with a filling-opening disposed between the opposite end portions of the flange and communicating with the oil-chamber, and a removable 25 closure-plug fitted in said filling-opening and

projecting externally of the adjacent end of the hub, and forming an obstruction in the opening of the flange.

2. A wheel having its hub provided with 30 an annular oil-chamber in communication with the spindle-receiving opening of the hub, there being a substantially cylindrical flange projected outwardly from the outer end of the hub and having a portion removed, the 35 oil-chamber being provided with a plurality of radial outwardly-directed enlargements forming sediment-collecting pockets, the inner ends of which are provided with cleaning-openings formed through the inner end of the 40 hub, one of the enlargements or pockets being located adjacent to and in alignment with the opening in the flange and provided in its front. end with a filling - opening formed through the front end of the hub and lying between the ends of the flange, and closure-plugs 45 for the openings in the ends of the pockets.

WESLEY M. SCOTT.
